MANUFACTURE OF CIGARETTE PAPER BLOCKS

Henri Chambon, Paris, France, assignor to Societe Anonyme de Anciens Etablissements L. Chambon, Paris, France, a society of France

Application March 20, 1936, Serial No. 69,985
In France April 16, 1935

6 Claims. (Cl. 270—41)

The present invention relates to the manufacture of cigarette paper blocks at a high velocity. The invention enables obtaining, in a single operation, entirely completed blocks at a rate which

5 may be beyond 800 blocks per minute. To this end a bundle or pile is formed with a number of strips of paper which is equal to the number of sheets constituting each block and then the said bundle is cut in sections, each of which will form a block.

10 According to one of the features of the invention, guide rollers are provided along the path of the bundle and said rollers are arranged parallel to the plane of the bundle and at an angle of about 45° to its axis.

15 The strips coming from the feeding reels reach the guide rollers, run over them and are supplied to the bundle. Preferably the strips which arrive at the guide rollers are in a plane which is substantially parallel to the plane of the bundle and their direction is substantially

20 at right angles to the direction of the bundle. It is advantageous to guide the strips along their path towards the guide rollers, for instance between two driving belts. The guide rollers are ad-

25 vantageously provided with means for adjusting their position by a displacement parallel to them-

25 selves and in a plane which is parallel to the plane of the bundle. In one embodiment the bundle is driven by a belt 44 upon which said bun-

30 dle is applied.

35 It is advantageous to guide the unwinding motion of the strips of paper by means of a flanged roll applied upon each reel at the point at which the strip is unrolled. In this case, it will be ad-

35 visable to arrange the reel so that it may be laterally displaced upon its supports.

In order to wrap the bundle with the container board which is intended to form the cover of the blocks, the said board may be supplied in the form of a strip passing between slopes provided in order

40 to fold said strip around the bundle.

45 It is understood that all the above arrangements and all such as may be further described may be considered separately or jointly as comprised in the scope of the invention.

45 By way of example and in order to facilitate the understanding of the invention an embodiment thereof is shown in the accompanying drawings in which

Figure 1 is a diagrammatical view in trans-

50 verse section of a machine according to the in-

vention.

Figure 2 is a sectional view of a flanged roll for

guiding the reels.

Figure 3 is a partial view showing the setting

55 of the reels in their bearings.

Figure 4 is a plan view of a guide roll.

Figure 5 is a front view of the machine.

Figure 6 is a diagrammatical plan view of the same.

The machine shown in the drawings comprises 5 a table 1 (Figure 1), having aligned on its side the reels such as 2, 3, provided with strips of cigarette paper.

Each reel is set on a winding drum 4 (Figures 1 and 3) having its axis supported on bearings provided on parallel supports 6, 7. Such supports are spaced from each other so that the reels 2 may move transversely between them, whilst the shaft 5 is longitudinally slidable on its bearings.

A flanged roll 8 (Figures 1 and 2) carried by an 15 arm 9 is applied at the periphery of the reel 2 at the point at which the strip of paper 10 is un- 15 wound, i. e. where said strip is leaving the reel. The arm 9 is pivoted on the axis 11 and is sub- 20 jected to the action of a spring 12 which tends to urge the roll 8 against the reel 2.

The zone of the reel at which the strip 10 is 25 unwound is maintained between the flanges 14, 15, of the roll 8. Consequently it cannot be displaced transversely and the strip 10 always remains in 25 the same vertical plane. The reels 2 may happen to be deformed or twisted and in such case the axis 5 will slide longitudinally on its bearings whilst the strip 10 remains unchanged owing to the roll 8.

The unwinding of the reel 2 is controlled by a 30 braking device comprising a band 16 secured at 17, carried over the reel 2 and stretched by a counterweight 18.

The reel 3 is arranged in the same way. How- 35 ever, the band 26 of the brake is secured at 27 on the arm 29 of the flanged roll 28. The strip 20 which is unrolled from such reel is aligned with the strip 10 for its passage between the rollers 19, 21 and subsequently between the two driving 40 belts 22, 23.

Only one of the reels 2, 3, may be unwound at 45 a time and in this case the other reel is set up and ready to come into operation in order to rapidly substitute one strip for the other when the first reel is emptied.

After leaving the driving belts 22, 23, the bundle 24 which comprises the strips 10 and 20 runs over a guide roller 25 (Figures 1, 4, 5 and 6) arranged substantially at 45°. The bundle is thus carried 50 on at right angles at 30 (Figure 4). For the adjustment of the position of said bundle 30, the roller 25 is arranged on a bearing 31 secured to the rods 32, 33, by means of the pins 34, 35, 36, arranged in order to provide for slight displace- 55

ments of the bearing 31. The proper position is obtained by unlocking the bolts through an adjusting screw 37 which is shown in dotted lines in Figure 4. The said screw enables moving the support in the direction of the arrow 54 without changing the obliquity of the cylinder 25.

Owing to said adjustment, the bundle 30 is exactly superimposed on a bundle 38 (Figures 5 and 6) which comes from the preceding reels. The apparatus comprises a row of upper reels 39, 40, 41, arranged side by side and with their axes such as 5 (Figure 1) in alignment with each other. Above the said row is arranged another row of reels 3, 42, 43. For sake of clearness, only a number of the reels of each row is shown in Figures 5 and 6, but in fact the upper and lower rows extend along the entire machine.

The bundle 38 is driven by a belt 44 running over the pulleys 45, 46. It travels from left to right (Figures 5 and 6) and is supplied with two strips at each roller 25. The total bundle coming out at 47 is constituted by a number of strips which is equal to the number of cigarette paper sheets which will be comprised in each block.

The said bundle is carried over a drum 48 (Figure 5) and returns from right to left. It is then provided with a board strip 49 intended to form the cover of the blocks. To this end, the strip 49 is wider (Figure 6) than twice the width of the bundle 47. The strip 49 is folded over the said bundle along the path comprised between the drum 48, and the folding means such as 50. The bundle thus wrapped is driven by the cylinders 51, 52, and subsequently sectioned by a device 53 which is diagrammatically shown at 53 (Figures 5 and 6).

Having now particularly described and ascertained the nature of my invention and in what manner the same is to be performed, I declare 40 that what I claim is:

1. An apparatus for manufacturing cigarette paper blocks comprising a series of drums for holding webs of cigarette paper, guiding means for the edges of each web located at the point where each web leaves its drum and means for mounting said drums so that said drums may rotate freely on their axes and move longitudinally of said axes.

2. An apparatus for manufacturing cigarette paper blocks comprising a drum for holding a web of cigarette paper, a roller, flanges upon said roller guiding the edges of the web of paper located at the point where said web leaves said drum, means urging said roller with said flanges against the web upon said drum and means for mounting said drum so that said drum may rotate freely on its axis and also move longitudinally of its axis.

3. An apparatus for manufacturing cigarette paper blocks comprising a series of drums for holding webs of cigarette paper, guiding means for the edges of each web located at the point where each web leaves its drum, means for mounting said drums so that said rollers may rotate freely on their axes and move longitudinally of said axes, endless feeding means between which said webs are led after leaving said drums, a direction changing roller for said webs for changing the direction of said webs after leaving said endless feeding means and endless feeding means for said webs located at substantially right angles to said first mentioned feeding means.

4. An apparatus for manufacturing cigarette paper blocks comprising a series of drums for holding webs of cigarette paper, means for mounting said drums so that said drums may rotate freely on their axes and move longitudinally of said axes, fixed guiding means for each web located at the point where each web leaves its drum, means for feeding said webs after leaving said guiding means, means for changing the direction of said webs after leaving said feeding means and a second feeding means for aligning all said webs in a compact bundle.

5. An apparatus for manufacturing cigarette paper blocks comprising a series of drums for holding webs of cigarette paper, means for mounting said drums so that said drums may rotate freely on their axes and move longitudinally of said axes, fixed guiding means for each web located at the point where each web leaves its drum, means for feeding said webs after leaving said guiding means, means for changing the direction of said webs after leaving said feeding means and a second feeding means for aligning all said webs in a compact bundle, and means for associating a cover strip with said bundle.

6. An apparatus for manufacturing cigarette paper blocks comprising a series of drums for holding webs of cigarette paper, means for mounting said drums so that said drums may rotate freely on their axes and move longitudinally of said axes, fixed guiding means for each web located at the point where each web leaves its drum, means for feeding said webs after leaving said guiding means, means for changing the direction of said webs after leaving said feeding means and a second feeding means for aligning all said webs in a compact bundle, means for associating a cover strip with said bundle, and means for cutting said bundle with associated cover strip into cigarette blocks.

HENRI CHAMBON.
